MOUNTING OR RECEPTACLE AND CIRCUIT
BREAKER FOR TUBES OR LAMPS AND
THEIR CIRCUITS

Herman Ruesch, Peoria, Ill.

Application April 23, 1945, Serial No. 589,870

4 Claims. (Cl. 315—254)

1

This invention pertains to yielding mountings and a circuit breaker for lamps and their electric circuits.

The main object of the invention is to provide yieldable mountings or receptacles in which to seat the extremities of a lamp and to combine with one of said receptacles a circuit breaker for the electric current, the said circuit breaker being automatically operated by seating of the lamp in a receptacle adjacent said circuit breaker to close said circuit and, conversely, to permit said breaker to open the circuit when and as the lamp is removed.

Another object is to mount a lamp receptacle adjacent an erected circuit breaker which forms part of the primary circuit of the usual transformer, whereby in seating the lamp in, or removing it from a receptacle, said circuit breaker will close or open said circuit, as the case may be, the receptacle being adapted to yield or flex in the direction of said circuit breaker.

That the invention may be fully understood the appended drawing is provided forming part hereof, wherein—Though a transformer is herein mentioned as part of an electric system to include a primary circuit and a secondary circuit it is to be understood that the use of any other system is contemplated herein which includes both types of circuits, and which may include a so called "ballast" or similar device serving a like purpose in the system.

Figure 1 is a plan of a structure showing the invention, said figure also showing diagrammatically, the wiring circuits involved.

Figure 2 is a plan of the same structure, but without the wiring diagram.

Figures 3 and 4 are elevations of parts illustrated in Figures 1 and 2, produced on a larger scale, or full size, said parts being shown in different positions in the two figures.

Figures 5 and 6, respectively, a front elevation and a plan of a yielding receptacle shown in the previous figures, and

Figure 7 is an elevation of opposed receptacles shown in the earlier figures together with a lamp suspended between them as appears in use.

It has been customary to provide in circuits for lamps of the type named a switch box, or "cut-out" box, which must be opened to reach a control switch for breaking the electric circuit prior to the removal of a lamp, this act having to be repeated after the lamp has been replaced. Such an arrangement is bulky and inconvenient, and is the source of trouble and annoyance each time a lamp is to be replaced. Again, the commonly used lamp

receptacles are of annoyance to an attendant, and much care is required in installing and removing a lamp.

Also of much importance is the fact that the attendant may often neglect to open the switch prior to the removal of the lamp, and thus the transformer circuit is exposed to damage by the continued flow of current in the primary circuit.

In order to avoid the uncertainties of such arrangements as mentioned the structure herein has been provided having advantages that will become apparent in the following description.

In the drawing, a support 1 carries the usual transformer 2 into which the current is led from the power line through a conductor 3, for example, that can be plugged into any convenient outlet, all without invention herein.

The novel portions include a pair of opposed spaced receptacles 4, 4' to receive the extremities of the lamp 5 and for transmitting current thereto in the usual way. Each receptacle in this instance may consist of a helically wound strong spring wire forming a cone into which an extremity of the lamp may be introduced, the large ends of the cones facing each other. One end of the coiled wire, or that at the large end, may terminate in an eye 6, for example, by which the cone may be mounted in an upright position on the support 1 so that the apices of the cones will lie in a line with each other. Preferably, at the small end of the cone the terminus of the wire, as 7, may assist in forming an abutment for the lamp extremity.

Since, of course, lamps are usually of different lengths the coned receptacles 4, 4' thus provided may be spaced apart any desired distance. Also, the receptacles may be grouped side by side to thereby accommodate banks of lamps in the usual manner.

Adjacent one of the receptacles as in Figures 3, 4 and 7, particularly, is erected a member 8 of insulating material fixed in position by any suitable means. Secured to said member at its upper end is one end of a spring 9 which in the present instance is extended downward toward the support 1. Fixed to the spring is one end of a lead-wire 11 whose other end is connected to the primary coil, not shown, of the transformer 2. On said member 8 is a contact portion 12 with which the spring at its end has contact on occasion, said portion 12 being connected into the primary circuit by a wire 13. Again, a wire 14 is

connected to and between the receptacle 4 and one side of the secondary coil, not shown, of the transformer, while a wire 15 connects the other side of the latter with the receptacle 4'. Through the connections described, or part of them, it is evident, of course, that the primary circuit can be opened or closed by the spring 9.

Attention is now drawn to the fact that, as shown, the receptacles 4, 4' due to the coiled-wire form thereof are expandable axially by the insertion of the lamp 5. In Figure 3 it is observed that when not under stress the receptacle 4 is a compact cone, the convolutions thereof substantially abutting each other, and that the spring 9 of the circuit breaker is normally distant from the contact portion 12, the primary circuit, therefore, being open. However, when the lamp 5 is seated in said receptacles 4, 4' the coils of both these members are expanded as shown in Figure 7 from the fact that the distance between the apices of the cones when the latter are unsprung is less than the length of the said lamp. In mounting the lamp one end thereof is first nested in the receptacle 4', sufficient pressure being exerted to permit the other end to pass to the center of the receptacle 4 and brought into the line therewith whereupon the receptacle 4' which is under stress will push the end at said receptacle 4 of the lamp into that receptacle for seating, and the apex of the cone will be moved toward and against the strip 10, and by the latter spring 9 is forced into intimate contact with the conducting portion 12, closing the previously open circuit.

It is to be understood, of course, that the receptacles 4, 4' may be identical in respect to reaction under stress, and that they are so spaced that the receptacle 4 and the pressure exerted by the receptacle 4' will be sufficient to bring about circuit closing.

While the particular structure of the receptacles described answer admirably the purpose intended it is possible to use some other form yielding like results. Thus it is not the intention to be confined necessarily to what has been shown and described in respect thereto. The same may be said in respect to other parts herein described.

In placing the circuit breaker 8, 9 in the primary circuit all current flow through the secondary coil of the transformer, or through any other electric system used, as earlier noted herein, is avoided naturally, so that no chance harm can be done to the latter by current flow were the circuit breaker otherwise connected during an interval when the lamp may not be in place.

I claim:

1. Means for mounting a lamp and for closing a circuit therethrough, including in its construction, and in combination with the primary and secondary coils of a transformer, a normally open circuit breaker connected in circuit with the primary coil, a receptacle erected adjacent the circuit breaker normally free thereof, part of said receptacle being yieldably extensible toward said circuit breaker adapted to abut upon the same to close the primary circuit therethrough by a lamp inserted at one end into said receptacle, and means to maintain elastic pressure endwise upon the lamp in the direction of said circuit breaker to maintain closed relation thereof, said receptacle and said means being connected with the secondary coil, closing the circuit through said lamp.

2. Means for mounting a lamp and for closing a circuit therethrough, including in its construction, and in combination with the primary and secondary coils of a transformer, a normally open circuit breaker connected in circuit with the said primary coil, a receptacle erected adjacent the circuit breaker normally free of the same, part of said receptacle being yieldingly extensible toward said circuit breaker and to abut upon the same to close the circuit therethrough by introduction of one end of a lamp into said receptacle, and a second receptacle at the other end of the lamp, the same adapted to exert a yielding pressure on said lamp in the direction of said circuit breaker to maintain a closed primary circuit, both receptacles being in circuit with said secondary coil through said lamp.

3. Means for mounting a lamp and for closing a circuit therethrough, including in its construction, and in combination with the primary and secondary coils of a transformer, a normally open circuit breaker connected in circuit with the primary coil, a receptacle erected adjacent the circuit breaker normally free thereof, said receptacle consisting of a helix of spring wire, part of said receptacle being yieldably extensible toward said circuit breaker adapted to abut upon the same to close the primary circuit therethrough by a lamp inserted at one end into said receptacle, and means to maintain elastic pressure endwise upon the lamp in the direction of said circuit breaker to maintain closed relation thereof, said receptacle and said means being connected with the secondary coil, closing the circuit through said lamp.

4. Means for mounting a lamp and for closing a circuit therethrough, including in its construction, and in combination with the primary and secondary coils of a transformer, a normally open circuit breaker connected in circuit with the said primary coil, a receptacle erected adjacent the circuit breaker normally free of the same, said receptacle consisting of a coned helix of spring wire, part of said receptacle being yieldingly extensible toward said circuit breaker and to abut upon the same to close the circuit therethrough by introduction of one end of a lamp into said receptacle, and a second receptacle at the other end of the lamp, the same adapted to exert a yielding pressure on said lamp in the direction of said circuit breaker to maintain a closed primary circuit, both receptacles being in circuit with said secondary coil through said lamp.
